(57) **CLAIM**

The ornamental design for a splatter shield, as shown and described.

DESCRIPTION

FIG. 1 is a front, top perspective view of a splatter shield showing a first embodiment of our new design;

FIG. 2 is a front, bottom perspective view thereof;

FIG. 3 is a front view thereof;

FIG. 4 is a rear view thereof;

FIG. 5 is a right side view thereof, the left side view being a mirror image of the right side view;

FIG. 6 is a top view thereof; and

FIG. 7 is a bottom view thereof.

FIG. 8 is a front, perspective view of a splatter shield showing a second embodiment of our new design;

FIG. 9 is a front, bottom perspective view thereof;

FIG. 10 is a front view thereof;

FIG. 11 is a rear view thereof;

FIG. 12 is a right side view thereof, the left side view being a mirror image of the right side view;

FIG. 13 is a top view thereof; and

FIG. 14 is a bottom view thereof.

FIG. 15 is a front, perspective view of the splatter shield showing a third embodiment of our new design;

FIG. 16 is a front, bottom perspective view thereof;

FIG. 17 is a front view thereof;

FIG. 18 is a rear view thereof;

FIG. 19 is a right side view thereof, the left side view being a mirror image of the right side view;

FIG. 20 is a top view thereof; and

FIG. 21 is a bottom view thereof.

FIG. 22 is a front, perspective view of the splatter shield showing a fourth embodiment of our new design;

FIG. 23 is a front, bottom perspective thereof;

FIG. 24 is a front view thereof;

FIG. 25 is a rear view thereof;

FIG. 26 is a right side view thereof, the left side view being a mirror image of the right side view;

FIG. 27 is a top view thereof; and,

FIG. 28 is a bottom view thereof.
